UNITED STATES PATENT OFFICE.

LEWIS C. NORTON, OF CHICAGO, ILLINOIS, ASSIGNOR TO NORTON DOOR CLOSER COMPANY, OF CHICAGO, ILLINOIS, A CORPORATION OF WEST VIRGINIA.

LEAK-STOP CONSTRUCTION.

Application filed June 5, 1922. Serial No. 565,955.

My invention relates to a leak-stop construction and more specifically to a leak-stop construction for the oscillatable shaft of a liquid or hydraulic door check. These door 5 checks are provided with a dash-pot chamber in which a liquid such as glycerin or the like is maintained, this liquid being at times subjected to extremely high pressures, which tends to force the liquid out around the 10 oscillatable shaft which connects with the operating arm of the door check.

One of the objects of my invention is to provide a leak-stop to prevent the escape of this liquid from the dash-pot chamber.

15 A further object of my invention is to provide a leak-proof construction which will not develop excessive friction.

A further object of my invention is to provide a leak-stop, which will be simple in 20 construction, durable and efficient in use, and cheap to manufacture.

Further objects will appear from the detailed description to follow and from the appended claims.

25 In the drawings in which several embodiments of my invention are shown—

Figure 1 is a perspective view showing a door check;

Fig. 2 is a central sectional view through 30 the door check;

Fig. 3 is a part sectional, part elevational view showing the pinion, shaft and packing gland;

Fig. 4 is a perspective view of the wedge 35 members;

Fig. 5 is a perspective view of the leather packing member;

Fig. 6 is a central sectional view showing 40 another form of leak-stop;

Fig. 7 is a central sectional view showing still another form of leak-stop; and

Fig. 8 is a detail view of the wedging washer shown in Fig. 7.

45 Referring now to the drawings in detail, and first to Figs. 1 to 5 inclusive, the door check shown therein comprises the casing member 10, having a dash-pot chamber 11 and a spring chamber 12, a dash-pot member or plunger 13, operating in the dash-pot 50 chamber and connected with a rack 14, a pinion 15, meshing with the rack 14, a shaft 16, secured to the pinion 15, an arm 17, secured to the shaft 16, a return spring 18 having one end secured to the wall of the 55 spring chamber 12 and the other end secured

to the sleeve 19 on the shaft 16, and a leak-stop construction at 20 for preventing the escape of liquid from the dash-pot chamber 11 into the spring chamber 12.

The action of the plunger 13 in the dash-pot chamber at certain stages in the operation causes a very high pressure of the oil or other liquid in the dash-pot chamber. The leak-stop construction at 20 is provided to prevent the liquid in the dash-pot chamber 60 from escaping around the shaft 16 into the spring chamber.

This leak-stop construction comprises a packing gland 21 threaded into the partition 22 between the dash-pot chamber and the spring chamber, a cupped annular leather packing 22^a (Fig. 5) surrounding the shaft 16, a plurality of arcuate wedge members 23 (Fig. 4) engaging the cupped annular packing 22^a, a coil compression spring 24 bearing 70 on the wedge members 23 to force them inwardly, and a packing gland nut 25 bearing on the upper end of the compression spring 24. The cupped annular packing 22^a comprises a cylindrical portion 26, which is 75 forced snugly against the shaft 16 by the action of the wedge members 23, and a tapering frusto-conical portion 27, which bears against the frusto-conical surface of the lower portion of the packing gland 21. 80 The cupped leather packing washer is constructed so that the grain side of the leather will be contiguous to the shaft 16, and also to the inner surface of the packing gland 21. 85 It has been found by test that this grain side of the leather is better, both for stopping the leak and resisting the wear, than the flesh side of the leather.

As clearly shown in Figs. 3 and 4, both the upper and lower faces of the wedge members 90 23 are tapered. Thus, the wedge members are urged inwardly not only by their tendency to slide down in along the inwardly tapering surface of the packing gland nut, but also by the action of the coil compression 100 spring on the sloping upper surfaces of the wedge members. It will be noted that the upper and lower faces of the arcuate wedge members are at quite a steep angle (about 60 degrees) so that there is a strong component tending to force the wedge members inwardly to squeeze the packing member 22 snugly against the shaft 16 to prevent leakage.

The construction shown in Fig. 6 is quite 110

similar to that just described, except that here an additional packing is provided at the upper end of the spring 24. The construction at the lower end of the spring is 5 precisely the same as that just described, comprising an annular cup-shaped leather packing member 22^a, and the arcuate wedge members 23. The packing at the upper end also includes an inverted annular cupped 10 packing member 22^a, and a set of wedge members 23, the spring 24 acting upwardly on the upper wedge members 23 and downwardly on the lower wedge members 23. The tapering portion 27 of the upper packing 15 member bears against the tapering inner surface 28 of the packing gland nut 29. The action of the spring 24 on the upper packing is just the same as the lower packing, the wedges 23 being forced inwardly 20 both by the action of the spring 24 and by the reaction of the packing gland nut.

In Fig. 7 is shown a construction in which the spring is dispensed with, the split wedging washer 30 in this form being engaged 25 directly by the tapering inner surface 31 of the packing gland 32.

It is obvious that the plurality of wedge members shown in Fig. 4 may be used interchangeably with the split wedging washer 30 in the various constructions shown.

While I have shown but three embodiments of my invention, it is obvious that it may be embodied in other forms as covered and defined by the appended claims.

Having thus described my invention, what I claim as new and desire to secure by Letters Patent of the United States is:—

1. The combination with a rotatable shaft, of a leak-proof packing construction 40 for said shaft comprising a packing gland having a conical surface surrounding said shaft, and an integral piece of flexible material shaped to provide a cylindrical portion immediately surrounding said shaft, 45 and a conical portion integral with said cylindrical portion and bearing against the conical portion of the packing gland, a plurality of arcuate wedge members located between the cylindrical portion and the 50 conical portion of the flexible piece, and means for forcing said wedge members downwardly whereby the conical surface of the packing gland will force them inwardly to bind the cylindrical flexible material 55 snugly against the shaft.

2. A rod packing construction comprising a rod, a packing gland surrounding said rod having an annular seating surface at the bottom and an integral packing member 60 of flexible sheet-like material shaped to

provide a cylindrical sleeve surrounding said rod, and a circular flange extending outwardly from said cylindrical sleeve and engaging said annular seating surface, and means for forcing said sleeve inwardly 65 against said rod and for forcing said circular flange against its annular seat.

3. A rod packing construction comprising a rod, a packing gland surrounding said rod having a conical seating surface 70 at the bottom and an integral packing member of flexible sheet-like material shaped to provide a cylindrical sleeve surrounding said rod, and a conical flange extending outwardly from said cylindrical sleeve and engaging said conical seating surface, and arcuate wedge means fitting between said sleeve and flange and movable inwardly and downwardly to force the sleeve snugly about the rod and force the conical flange snugly 80 to its conical seat.

4. A rod packing construction comprising a rod, a packing gland surrounding said rod having a conical seating surface at the bottom and an integral packing member of 85 flexible sheet-like material shaped to provide a cylindrical sleeve surrounding said rod, and a conical flange extending outwardly from said cylindrical sleeve and engaging said conical seating surface, and arcuate wedge means fitting between said 90 sleeve and flange and movable inwardly and downwardly to force the sleeve snugly about the rod and force the conical flange snugly to its conical seat, said arcuate wedge 95 means having conical upper surfaces, and a packing gland nut having a conical lower surface engaging the upper conical surface of the wedge means to force the wedge means inwardly toward the rod and downwardly toward the conical seating surface.

5. A rod packing construction comprising a rod, a packing gland surrounding said rod, having a conical seating surface at the bottom, a packing sleeve in said gland surrounding said rod, arcuate wedge means in said gland surrounding said packing sleeve, a packing gland nut having a conical lower surface, said wedge means having a conical upper surface cooperating with the 100 conical lower surface of the packing gland nut and having a conical lower surface cooperating with the conical seating surface at the bottom of the gland whereby as the nut is moved downwardly, the arcuate 105 wedge means will be forced inwardly.

In witness whereof, I have hereunto subscribed my name.

LEWIS C. NORTON.
